UNITED STATES PATENT OFFICE.

ERICK D. BJORK, OF HENRIETTE, MINNESOTA.

MITER-BOX.

No. 876,316.

Specification of Letters Patent.

Patented Jan. 14, 1908.

Application filed December 18, 1905. Serial No. 292,250.

To all whom it may concern.

Be it known that I, ERICK D. BJORK, a citizen of the United States, residing at Henriette, in the county of Pine, State of Minnesota, have invented certain new and useful Improvements in Miter-Boxes; and I do hereby declare the following to be a full, clear, and exact description of the invention, such as will enable others skilled in the art to which it appertains to make and use the same.

This invention relates to miter boxes and has for its object to provide a miter box arranged to cut material at different angles, and so constructed that a piece of material may be cut at an angle to both its faces and its edges.

Other objects and advantages will be apparent from the following description.

In the drawings forming a portion of this specification, and in which like numerals of reference indicate similar parts in the several views, Figure 1 is a top plan view of the present miter box, the parts being set to cut a board vertically and at a slanting angle to its edges. Fig. 2 is a front view, the uprights being shifted into position to cut a board at a slanting angle to the faces. Fig. 3 is a section on line 3—3 of Fig. 1, taken longitudinally of the supporting member. Fig. 4 is a detail section on line 4—4 of Fig. 2, showing the means for adjusting the sliding plate.

Referring now to the drawings, the present invention comprises a base member 5 having a longitudinal passage therein in which there is revolvably engaged a rod 6 extending at its ends beyond the member 5 and upon the ends, there are keyed parallel uprights 7 which include each, a pair of inner and outer telescoping members, 8 and 9 respectively. The members 8 extend above the members 9 and, in these upwardly extending portions, there are formed longitudinal slots 10 which open at their ends through the mutually adjacent faces of the members, and are thus registering. These slots are arranged for the reception of the back rib of a back saw. The uprights 7 have longitudinal slits 13 therein which communicate at their upper ends with the lower portions of the slots 10 and receive the blade of the back saw, the arrangement being such that the saw is held with its teeth in spaced relation to the bottom of the slits 13.

As will be seen, the uprights 7 are shiftable pivotally with respect to the member 5 and a sliding latch 14 is carried by the member and

is arranged for engagement with notches 15 formed in one of the uprights to hold the uprights at different points of their pivotal movement. This latch is held yieldably in operative position by a spring 15 engaged between the inner end of the latch and an upwardly extending block 15' carried by the member 5. As shown, in Fig. 3, the latch 14 is provided with a longitudinal socket 14' into which extends the outer end of a laterally-projecting finger 15^b formed upon the block 15', the spring 15 embracing said finger.

A supporting plate or bed 16 is provided and at its rearward side has a vertical opening 17 which receives pivotally therewithin a pin 18 carried by a block 19 which is removably engaged with the member 5 adjacent to the opposite end of this member from the latch 14, the base member being thus pivoted beneath the bed 16, and extending forwardly and rearwardly beyond the latter, the bed lying between the uprights 7.

The bed has a depending arcuate rack bar 20 which is arranged for engagement by a latch 21 carried by the base member 5 to hold the base member at different points of its movement with respect to the bed, this latch being pivoted in a bracket 22 carried by the side of the base member and being held yieldably in operative position by a spring 23 engaged between the forward end portion of the latch and an ear 24 extending laterally from the base member above the latch.

The pin 18 extends above the bed 16 and has engaged therewith the rearward end of a longitudinally slotted plate 26 which extends transversely of the bed, resting at its forward end upon the block 15', to which it is secured. This plate 26 is thus held stationary with respect to the base member 5 and is movable therewith pivotally with respect to the bed 16.

At opposite sides of the plate 26, the bed 16 has portions 16' which are elevated above the central portion thereof, the mutually adjacent edges of these elevated portions converging rearwardly and being beveled downwardly and toward each other and the arrangement is such that the base member and the uprights 7 may be shifted with respect to each other and with respect to the bed to bring the saw into position to rest against one or the other of these beveled faces.

It will be seen that, by reason of the peculiar structure, it is possible to vary the angle of the vertical dimension of the saw with re-

spect to the bed by shifting the uprights 7 with respect to the base member; and it is also possible to vary the angle of the longitudinal or horizontal dimension of the saw 5 with respect to the bed by shifting the base member 5 with respect to the bed. It is thus possible to cut a piece of material at two angles simultaneously.

The plate 26 is provided, as will be readily 10 understood, to support the portions of material lying between the upwardly extending portions 16' of the bed.

Slides 30 are carried by upwardly extending back members 31 which are secured to 15 the bed, the inner ends of these back members terminating at the innermost portions of the portions 16' of the bed. The mutually adjacent end faces of these back portions converge downwardly as shown, to permit of 20 the above described adjustment of the saw, and the slides 30 are movable to extend at times beyond the inner ends of these back members to receive thereagainst and support short pieces of material to be cut. 25 Means indicated at 32 is provided for each of the slides to hold it at different points of its movement.

What is claimed is:

In a miter box, the combination, with a 30 bed, of a base member provided therebeneath and having a longitudinal passage formed therethrough; a rod revolvably en-

gaged in said passage and projecting at opposite ends beyond said base member; a saw-receiving member secured to each end of said 35 rod, one of said saw-receiving members being provided with notches; a latch slideable upon the base member and provided with a longitudinal socket; a block mounted upon the base member in alignment with the latch and 40 having a laterally-projecting finger extending into said socket; a spring interposed between the latch and the block for yieldingly holding the latch in engagement with one of said notches, the spring being carried by the 45 block finger; a depending arcuate rack secured to the bed and concentric with the base member; a bracket secured to one side of the base member; a latch pivoted centrally in said bracket for movement of one of 50 its ends into and out of engagement with said rack; a laterally-projecting ear carried by the base member directly above the opposite end of the latch; and a spring interposed between the ear and the last-mentioned end of 55 the latch, for holding the first-mentioned end thereof in engagement with the rack.

In testimony whereof, I affix my signature, in presence of two witnesses.

ERICK D. BJORK.
